INTERNAL-COMBUSTION ENGINE OF THE
FREE PISTON TYPE

Harold Oatridge Farmer, Hounslow, England, assignor to Alan Muntz & Company Limited, Hounslow, England, a company of Great Britain

Application March 9, 1943, Serial No. 478,503
In Great Britain March 2, 1942

19 Claims. (Cl. 123—46)

1

This invention relates to internal-combustion engines of the free-piston type. The primary moving parts of such free-piston engines consist of a piston assembly, or usually an opposed pair of such assemblies and the connecting linkage which constrains them to move in synchronism. These parts are unconstrained by any continuously rotatable crank-shaft, though the synchronising linkage may include a crank-shaft which is arranged to oscillate through a limited angle. Generally this angle is less than 180°, so that neither the inner nor the outer dead point of the motion of the piston assemblies is fixed by the synchronising linkage. Dead points which are not so fixed will hereinafter be termed "indeterminate" dead points. In special cases the crank-shaft may be arranged to oscillate through an angle between 180° and 360°, in which case one of these dead points is fixed by the synchronising linkage and the other is indeterminate.

The primary moving parts come to rest in the dead points, and for short periods on each side of indeterminate dead points the speeds of all these moving parts are relatively very low. Furthermore, with engines operating on a variable load, the positions occupied by these parts at indeterminate dead points vary with variation in the operating conditions of the engine. Consequently such moving parts cannot be employed directly to operate auxiliary mechanism, such for example as a fuel-injection pump of a compression-ignition free-piston engine, which is required to function at an accurately determined instant in the engine cycle at or near an indeterminate dead point.

An object of this invention is to provide an improved method and means of overcoming this difficulty.

According to this invention, an operation required to take place at a time including or near an indeterminate dead point in the cycle of a free-piston engine is performed by the agency of kinetic energy which is transferred from the primary moving parts of the engine during their acceleration and which is thereafter stored during the subsequent retardation of such parts until the operation takes place.

A free-piston engine according to this invention includes an inertia member operatively connected to the primary moving parts of the engine in such a manner that the inertia member is accelerated by the motion of said parts during the first part of one of their strokes that precedes their occupation of an indeterminate dead point and is free to overrun said parts during a

2

subsequent part of the same stroke, means being provided which co-operate with the inertia member by retarding it at a predetermined point in such overrunning motion and using the kinetic energy thereby taken from the inertia member to perform an auxiliary function, such for example as to operate a fuel-injection pump or to time at least one of the limits of the delivery period of fuel-injection means.

10 Another object is to provide means for controlling the movement of the inertia member as it approaches each end of its stroke.

Another object is to provide a compact and robust mechanism incorporating the inertia member and the means for driving it and for causing it to perform the auxiliary function.

15 Further objects and advantages of the invention will be apparent from the following description of an embodiment of the invention given 20 with reference to the accompanying drawings, as applied to the drive of a fuel-injection pump of a two-stroke compression-ignition air-compressor of the opposed-piston type. In the drawings:

Fig. 1 is a diagrammatic sectional side elevation 25 of the air-compressor,

Fig. 2 is a side elevation of part of the compressor shown in Fig. 1, with part of the casing broken away and with the fuel-injection pump drive unit removed,

30 Fig. 3 is an end elevation of the same compressor, some parts being shown in section on the line 3—3 in Fig. 1,

Figs. 4, 5, 6 and 7 show diagrammatically the fuel-injection pump and its drive mechanism in 35 four different positions.

Fig. 8 is a graph (not to scale) illustrating the operation of this drive mechanism,

Fig. 9 is a sectional side elevation, taken on the lines 9—9 in Figs. 3 and 10, showing this drive 40 mechanism in more detail,

Fig. 10 is a sectional end elevation taken on the line 10—10 in Fig. 9, and

Fig. 11 is an inverted plan in section on the line 11—11 in Fig. 9.

45 The air-compressor shown in Figs. 1, 2 and 3 is generally of known type and includes a power cylinder 20 having inlet ports 21 and exhaust ports 22. A casing 23 surrounding the power cylinder forms a scavenge air receiver communicating directly with the inlet ports 21. At one end of the casing 23 is a compressor cylinder 24, and at the other end a pneumatic cushion cylinder 25.

The primary moving parts of the compressor 50 consist of two opposed free-piston assemblies and

the synchronising linkage which constrains them to reciprocate equally and oppositely. One of these piston assemblies consists of a power piston 26 controlling the inlet ports 21, and rigidly coupled by a rod 27 to a compressor piston 28 operating in the cylinder 24. The other piston assembly consists of a power piston 29 controlling the exhaust ports 22 and rigidly coupled by a rod 30 to a cushion piston 31 operating in the cylinder 25.

The synchronizing linkage includes two levers 32 and 33 capable of oscillating equally and oppositely about their mid points on a common horizontal axis which is perpendicular to the common longitudinal centre line of the two piston assemblies. The ends of the lever 32 are connected by connecting rods 34 and 35 respectively to two crossheads 36 and 37 fixed to the piston rods 27 and 30 and maintained horizontal by arms 38 and 39 sliding in guideways 40 and 41 formed on the casing 23. The ends of the lever 33 are likewise connected by connecting rods 42 and 43 respectively to the crossheads 36 and 37.

A fuel-injection nozzle 44 is supplied by a fuel-injection pump 45 of known type, provided with the usual adjusting member 46 for control of the quantity injected. The compressor cylinder 24 is double acting; the outer face of the compressor piston 28 draws in air through inlet valves such as 47 and delivers it through valves such as 48 to a compressed-air receiver (not shown), while the inner face of this piston draws in scavenging air through valves such as 49 and delivers it to the scavenging air receiver through valves such as 50.

Figs. 1 and 2 show the compressor at the inner dead point of the free pistons. During the expansion stroke of the power pistons, the synchronizing levers 32 and 33 are first accelerated counter-clockwise and clockwise respectively as viewed in Figs. 1 and 2, and thereafter retarded, their angular velocity being roughly directly proportional to the linear velocity of the free pistons. When the free pistons attain their outer dead point, the synchronizing levers will have been displaced through roughly a right angle. The power cylinder 20 having been scavenged, the free-pistons execute their in stroke, under the influence of the energy stored during their out stroke, in the air compressed in the cushion cylinder 25 and in the clearance volume of the outer end of the compressor cylinder 24, the synchronizing levers 32 and 33 returning to the positions shown at an angular velocity varying roughly in direct proportion to the linear velocity of the free pistons.

The drive mechanism for the fuel-injection pump 45 is contained in a case 51 (Fig. 3) and is actuated by a pivot shaft 52 of the synchronizing lever 33. Figs. 4 to 7 show this mechanism in different configurations, and it is convenient to refer to Fig. 6, which shows the configuration at the inner dead point of the free pistons, corresponding to Figs. 1 and 2. A driver 53, shown diagrammatically by heavy black lines, is rigid with the shaft 52, so that its angular velocity is also roughly directly proportional to the linear velocity of the free pistons. The inertia lever 54, which is arranged to move in a plane parallel to the plane of movement of the driver 53, has one end pivotally connected at 55 to the driver at a point displaced from the axis of oscillation of the driver. Relative movement between the driver 53 and the inertia lever 54 is limited by arranging the oscillating shaft 52 to which the

driver is fixed as an abutment passing with clearance through an eye 56 in the inertia lever. A weight 57 is rigid with the inertia lever 53 and is disposed on the side of the eye 56 remote from the pivoted connection 55.

The axis of a vertically displaceable tappet 58 actuating the fuel-injection pump 45 is perpendicular to the axis of the shaft 52, and is roughly perpendicular to the longitudinal centre line of the driver 53 when the latter is in the position shown in Fig. 6 corresponding to inner dead point at full load. The tappet 58 is so connected to the inertia lever 54 that it is constrained to follow the vertical component of the displacement of the point on the inertia lever that traverses the axis of oscillation of the driver. Thus the tappet is coupled to the inertia lever by a connecting link 59 one end of which is carried on a ring journal 60 co-axial with the eye 56 in the inertia lever and the other end of which is pivotally connected at 61 to the tappet.

The buffer for checking the movement of the inertia lever 54 at the end of the stroke in which fuel-injection occurs, consists of a laminated cantilever spring 62, fixed to the driver 53 and positioned to be engaged by a pin 63 on the inertia lever as the latter comes near to one end of its displacement relative to the driver.

The buffer for checking the movement of the inertia lever in the opposite sense is a hydraulic dash-pot device having one element 64 mounted on the driver and the other element 65 coupled to a pin 66 on the inertia lever by a connection 67 providing lost motion, the arrangement being such that the dash-pot imposes a resistance to the movement of the inertia lever relative to the driver as the former comes near to the other end of its displacement.

The fuel injection pump 45 has an inlet port 68 controlled by its plunger 69, which is urged in the direction of its suction stroke by a spring 70. During the delivery stroke of the plunger, after the inlet port 68 has closed, fuel is delivered through a non-return valve 71 until a spill port 72 in the plunger comes into register with a spill port 73 in the pump body, thus relieving the delivery pressure.

The operation of the fuel-pump drive mechanism will be described with reference to the graph in Fig. 8, in which are plotted, on a time base showing one complete cycle from an outer dead point (O. D. P.) through the subsequent inner dead point (I. D. P.) to the next outer dead point:

Angular displacement of the driver 53 denoted by D_D ,

Angular displacement of the inertia lever 54 denoted by D_W ,

Angular velocity of the driver denoted by V_D ,

Angular velocity of the inertia lever denoted by V_W ,

Angular acceleration of the driver denoted by F_D , and

Angular acceleration of the inertia lever denoted by F_W .

At the outer dead point of the free pistons (O. D. P. in Fig. 8) the driver 53 is stationary in the position shown in Fig. 4 and it has a high acceleration in a positive sense (counterclockwise as seen in Fig. 4), and the inertia lever 54 is at what will be termed the trailing limit of its range of movement relative to the driver. The driver therefore accelerates the inertia lever up to its maximum angular velocity (t_1 in Fig. 8). When the acceleration of the driver becomes negative, which occurs early in the second half

of the compression stroke, the weight 57 on the inertia lever continues to move at an angular velocity which falls relatively slowly, with the result that the inertia lever begins to move, relatively to the driver, about its pivoted connection 55 to the latter, advancing the fuel-injection pump tappet 58 and the plunger 69, and compressing the plunger spring 70. After this tappet has moved through a predetermined distance, the fuel-injection period commences, at time t_2 in Fig. 8, the power required to actuate the pump being supplied by the kinetic energy of the weight 57 which is thereby retarded. Fig. 5 shows the configuration at the beginning of the fuel-injection period. The fuel-injection period continues while the pistons pass through inner dead point (Fig. 6), until the tappet has advanced through the further distance required to open the spill ports 72 and 73. The end of the fuel-injection period occurs at time t_3 in Fig. 8. Thereafter the weight 57 continues to move at a substantially constant velocity for a short distance. At time t_4 in Fig. 8, before the inertia lever has reached the leading limit of its range of movement relative to the driver, the buffer spring 62 is engaged by the pin 63 and the weight is accordingly subjected to a short but high negative acceleration. The weight is thereby arrested and immediately moved at a rapidly increasing velocity in the opposite direction. When the inertia lever disengages from the buffer spring at time t_5 in Fig. 8, the weight continues to move at a substantially constant velocity, catching up the driver. In the latter half of the expansion stroke the driver is again subject to acceleration in the positive sense, and at time t_6 in Fig. 8 the pin 66 takes up the lost motion in the connection 67 (Fig. 7) and the inertia lever is prevented by the dash-pot device 64, 65, from returning with excessive shock to the trailing limit of its range of travel relative to the driver. The inertia lever and the driver begin to move in unison again at time t_7 in Fig. 8.

Figs. 9, 10 and 11 show the fuel-injection pump drive mechanism in greater detail, the configuration being that at inner dead point at full load of the air compressor. The pivot shaft 52 of the synchronising lever 33, which oscillates in synchronism with the engine pistons, is journaled at 74 in the case 51 and at 75 in a cover 76 of this case. The driver 53 has a hub portion 77 provided with internal splines engaged with a splined portion of the shaft 52, so that the driver 53 and the lever 33 are constrained to oscillate in unison. Oil under pressure is admitted at a union 78 in the cover 76 and flows, through a bore 79 and a port 80 in the shaft 52, and through a non-return valve 81 and a duct 82 in the driver 53, to the cylinder 64 of the dash-pot device. Since oil can flow freely into the head of the dash-pot cylinder, the device imposes no resistance to outward movement of its piston 65. This piston is hollow and its head is provided with a leak port 83 co-operating with a tapered needle 84 fixed to the cylinder head. This port opens into a hollow non-return valve 85, and an exhaust port 86 in the piston registers with an exhaust port 87 in the cylinder. The non-return valve 85 prevents air from being sucked into the dash-pot cylinder during outward movement of its piston. During inward movement of the piston the oil trapped in the cylinder by the non-return valve 81 is forced to flow through the leak port 83 and the valve 85, and the needle 84 is so shaped as to vary the effective area of the leak in accordance with the relative displacement of the piston 65 and the cylinder 64.

in such a manner that a substantially uniform force is imposed as the relative speed of the inertia lever and the driver falls. This is indicated by the horizontal portion of the curve Fw between t_6 and t_7 in Fig. 8.

The inertia lever consists of two arms 54A and 54B fixed to a pivot pin 55 which is rotatable in bearing in the driver 53, and these arms carry respectively two weights 57A and 57B which are bridged by the pins 63 and 66. Each of the arms 54A and 54B is provided with a hollow boss (Fig. 10) the interior surface of which forms the eye 56 that co-operates with the shaft 52 to limit the relative displacement of the inertia lever and the driver; the exterior surfaces of these bosses form the ring journals for the big ends of twin connecting rods 59A and 59B actuating the fuel-pump tappet 58.

The buffer spring 62 that is mounted on the driver is supplemented by a pair of buffer springs 88A and 88B which are mounted on the case 51 and which co-operate with lugs 89A and 89B formed on the rods 59A and 59B.

The mechanism described by way of example has the advantage that it can be designed to operate with standard types of fuel-injection pumps that are now commercially available.

The invention may be similarly applied to a timing device for determining the beginning or the end or both of a fuel-injection period in a free-piston engine having a fuel-injection device, the pump of which is operated by means other than the inertia member, such for example as a small gas motor energised by the working fluid compressed in the engine combustion chamber, such as described for example in my copending U. S. patent application Serial No. 376,259, filed January 28, 1941, now Patent No. 2,351,414, June 13, 1944.

I claim:

1. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke, such that at least one of its dead points is indeterminate, an auxiliary member for performing a function auxiliary to the operation of said engine, an inertia member, an operative connection between said inertia member and said primary moving parts for imparting to said inertia member an acceleration by the motion of said parts during the first part of one of their strokes that precedes their occupation of said indeterminate dead point, said connection serving to permit said inertia member to overrun said parts during a subsequent part of the same stroke, and means operatively associated with said auxiliary member and capable of co-operating with said inertia member by retarding it at a predetermined point in such overrunning motion and using the kinetic energy thereby taken from said inertia member to actuate said auxiliary member.

2. An internal-combustion engine having a power cylinder, means for injecting fuel into said cylinder, a compressor cylinder, primary moving parts including a power piston and a compressor piston co-operating with said cylinders respectively and connected together for operation in unison as a free-piston assembly capable of reciprocating through a variable stroke such that the inner dead point of said power piston is indeterminate, an inertia member, an operative connec-

tion between said inertia member and said primary moving parts for imparting to said inertia member an acceleration by the motion of said parts during the first part of one of their strokes that precedes their occupation of said indeterminate dead point, said connection serving to permit said inertia member to overrun said parts during a subsequent part of the same stroke, and means operatively associated with said fuel-injection means and capable of co-operating with said inertia member by retarding it at a predetermined point in such overrunning motion and using the kinetic energy thereby taken from said inertia member to actuate said fuel-injection means.

3. An internal-combustion engine having a power cylinder, a system for injecting fuel into said cylinder, said system including means for timing at least one of the limits of the delivery period of said system, a compressor cylinder, primary moving parts including a power piston and a compressor piston co-operating with said cylinders respectively and connected together for operation in unison as a free-piston assembly capable of reciprocating through a variable stroke, such that the inner dead point of said power piston is indeterminate, an inertia member, an operative connection between said inertia member and said primary moving parts for imparting to said inertia member an acceleration by the motion of said parts during the first part of one of their strokes that precedes their occupation of said indeterminate dead point, said connection serving to permit said inertia member to overrun said parts during a subsequent part of the same stroke, and means operatively associated with said timing means and capable of co-operating with said inertia member by retarding it at a predetermined point in such overrunning motion, and using the kinetic energy thereby taken from said inertia member to actuate said timing means.

4. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillable inertia member, an operative connection between said inertia member and said primary moving parts for imparting to said inertia member an acceleration by the motion of said parts during the first part of one of their strokes that precedes their occupation of said indeterminate dead point, said connection serving to permit said inertia member to overrun said parts during a subsequent part of the same stroke, means operatively associated with said auxiliary member and capable of co-operating with said inertia member by retarding it at a predetermined point in such overrunning motion and using the kinetic energy thereby taken from said inertia member to actuate said auxiliary member and at least one buffer for checking movement of said inertia member as it approaches each end of its stroke.

5. An internal-combustion engine having a power cylinder, a compressor cylinder, primary moving parts including a power piston and a compressor piston co-operating with said cylinders respectively and connected together for operation in unison as a free-piston assembly capable of

reciprocating through a variable stroke, such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said inertia member by retarding it at a predetermined point in such overrunning motion and using the kinetic energy thereby taken from said inertia member to actuate said auxiliary member and at least one buffer arranged to react on said oscillatory driver for checking movement of said inertia member as it approaches each end of its stroke.

6. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said inertia member by retarding it at a predetermined point in such overrunning motion and using the kinetic energy thereby taken from said inertia member to actuate said auxiliary member, and a resilient buffer arranged to react on said oscillatory driver for checking such overrunning motion of said inertia member relative to said oscillatory driver.

7. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke, such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said

inertia member by retarding it at a predetermined point in such overrunning motion and using the kinetic energy thereby taken from said inertia member to actuate said auxiliary member, a resilient buffer arranged to react on said oscillatory driver for checking such overrunning motion of said inertia member relative to said oscillatory driver, and a buffer in the form of a fluid dash-pot device arranged to react on said oscillatory driver for checking the return motion imparted to said inertia member by said resilient buffer.

8. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said inertia member by retarding it at a predetermined point in such overrunning motion and using the kinetic energy thereby taken from said inertia member to actuate said auxiliary member, a resilient buffer arranged to react on said oscillatory driver for checking such overrunning motion of said inertia member relative to said oscillatory driver, and a buffer in the form of a fluid dash-pot device arranged to react on said oscillatory driver for checking the return motion imparted to said inertia member by said resilient buffer, said dash-pot device having an automatically variable leak calibrated to maintain a substantially uniform resistance as the relative speed of said inertia member and said oscillatory driver falls.

9. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said inertia member by retarding it at a predetermined point in such overrunning motion and using the kinetic energy thereby taken from said

inertia member to actuate said auxiliary member, a resilient buffer arranged to react on said oscillatory driver for checking such overrunning motion of said inertia member relative to said oscillatory driver, a stationary part, and a supplementary buffer arranged to react on said stationary part for checking said overrunning motion.

10. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillable inertia member, an operative connection including an oscillatory driver between said inertia member and said primary moving parts for imparting to said inertia member an acceleration by the motion of said parts during the first part of one of their strokes that precedes their occupation of said indeterminate dead point, said driver providing lost motion to permit said inertia member to overrun said parts during a subsequent part of the same stroke, means operatively associated with said auxiliary member and capable of co-operating with said inertia member by retarding it at a predetermined point in such overrunning motion, and using the kinetic energy thereby taken from said inertia member to actuate said auxiliary member, a resilient buffer arranged to react on said oscillatory driver for checking such overrunning motion of said inertia member relative to said oscillatory driver, a buffer in the form of a fluid dash-pot device arranged to react on said oscillatory driver for checking the return motion imparted to said inertia member by said resilient buffer, a stationary part, and a supplementary buffer arranged to react on said stationary part for checking said overrunning motion.

11. An internal-combustion engine having a power cylinder, a compressor cylinder, primary moving parts including a power piston and a compressor piston co-operating with said cylinders respectively, and connected together for operation in unison as a free-piston assembly capable of reciprocating through a variable stroke such that at least one of its dead points is indeterminate, an auxiliary member for performing a function auxiliary to the operation of said engine, an oscillatory driver operatively connected with said primary moving parts, an inertia member in the form of a relatively massive lever which is pivotally connected to said oscillatory driver in such a manner that at such pivotal connection said lever is reciprocated substantially transversely to its length, means for limiting displacement of said lever relative to said oscillatory driver, and means operatively associated with said auxiliary member and capable of co-operating with said lever by retarding its motion, and thereby transferring energy from said lever to actuate said auxiliary member.

12. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke, such that at least one of its dead points is in-

determinate, an auxiliary member for performing a function auxiliary to the operation of said engine, an oscillatory driver operatively connected with said primary moving parts, an inertia member in the form of a relatively massive lever which is pivotally connected to said oscillatory driver in such a manner that at such pivotal connection said lever is reciprocated substantially transversely to its length, means for limiting displacement of said lever relative to said oscillatory driver, and means operatively associated with said auxiliary member and pivotally connected to a point on said lever located between said pivotal connection and the free end of said lever, said last-mentioned means being responsive to transverse displacement of said point for transferring energy from said lever to actuate said auxiliary member.

13. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke, such that at least one of its dead points is indeterminate, an auxiliary member for performing a function auxiliary to the operation of said engine, an oscillatory crank having a crank pin and operatively connected with said primary moving parts, a relatively massive lever pivotally mounted on the pin of said crank with its free end projecting beyond the axis of said crank on the side thereof opposite to said pin, means for limiting displacement of said lever relative to said crank, and means for operatively connecting said auxiliary member and said lever and capable of following a component of the motion of a point on said lever that is capable of coinciding with the axis of said crank.

14. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke, such that at least one of its dead points is indeterminate, an oscillatory auxiliary member for performing a function auxiliary to the operation of said engine, an oscillatory crank having a crank pin and operatively connected with said primary moving parts, a relatively massive lever pivotally mounted on the pin of said crank with its free end projecting beyond the axis of said crank on the side thereof opposite to said pin, means for limiting displacement of said lever relative to said crank, and a member connecting with said auxiliary member and pivotally connected to said lever at an axis capable of coinciding with the axis of said crank.

15. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an oscillatory auxiliary member for performing a function auxiliary to the operation of said engine, an oscillatory crank having a crank pin and operatively connected with said primary moving parts, a relatively massive lever pivotally mounted on the pin of said crank with

its free end projecting beyond the axis of said crank on the side thereof opposite to said pin, an abutment member co-axial with said crank, a ring journal rigid with said lever and forming an eye co-operating with said abutment member for limiting angular displacement of said lever relative to said crank, and a link connecting said auxiliary member to said ring journal.

16. An internal-combustion engine having a power cylinder, a compressor cylinder, primary moving parts including a power piston and a compressor piston co-operating with said cylinders respectively and connected together for operation in unison as a free-piston assembly capable of reciprocating through a variable stroke such that at least one of its dead points is indeterminate, an auxiliary member for performing a function auxiliary to the operation of said engine, an oscillatory crank having a crank pin and operatively connected with said primary moving parts, a relatively massive lever pivotally mounted on the pin of said crank with its free end projecting beyond the axis of said crank on the side thereof opposite to said pin, means for limiting displacement of said lever relative to said crank, and means for operatively connecting said auxiliary member and said lever and capable of following a component of the motion of a point on said lever that is capable of coinciding with the axis of said crank, the relationship of said crank to said primary moving parts being such that said last-mentioned means are arranged to be displaced substantially normally to a plane containing the axes of said crank and its pin when said crank is in the position corresponding to an indeterminate dead point.

17. An internal-combustion engine having a power cylinder, a system for injecting fuel into said cylinder, said system including means for timing at least one of the limits of the delivery period of said system, a compressor cylinder, primary moving parts including a power piston and a compressor piston co-operating with said cylinders respectively, and connected together for operation in unison as a free-piston assembly capable of reciprocating through a variable stroke such that the inner dead point of said power piston is indeterminate, an oscillatory crank having a crank pin and operatively connected with said primary moving parts, a relatively massive lever pivotally mounted on the pin of said crank with its free end projecting beyond the axis of said crank on the side thereof opposite to said pin, means for limiting displacement of said lever relative to said crank, and means connecting said timing means and said lever and capable of following a component of the motion of a point on said lever that is capable of coinciding with the axis of said crank and thereby imparting to said timing means a control movement from said lever while it is overrunning said crank during the latter part of the stroke of said pistons immediately preceding their occupation of said indeterminate inner dead point.

18. An internal-combustion engine having a power cylinder, a fuel-injection nozzle opening into said power cylinder, a fuel-injection pump for supplying said nozzle, a compressor cylinder, primary moving parts including a power piston and a compressor piston co-operating with said cylinders respectively and connected together for operation in unison as a free-piston assembly capable of reciprocating through a variable stroke, and means connecting said fuel-injection pump and said lever and capable of following a com-

13

ponent of the motion of a point on said lever that is capable of coinciding with the axis of said crank, and thereby imparting to said pump a control movement from said lever while it is overrunning said crank during the latter part of the stroke of said pistons immediately preceding their occupation of said indeterminate inner dead point.

19. An internal-combustion engine of the free-piston type as hereinbefore defined having a power cylinder, a power piston slidable in said cylinder through strokes of variable length with

10

14

an indeterminate dead point, a driver operatively connected with said piston, an inertia member co-operating with said driver for receiving acceleration therefrom during the first part of a stroke

5 immediately preceding said indeterminate dead point, and means for performing an operation auxiliary to the working of said engine, said inertia member being capable of imparting motion to said last-mentioned means during the second part of said stroke.
